UNITED STATES PATENT OFFICE.

JOHN J. SHIRKEY, OF CHICAGO, ILLINOIS.

ICE-REMOVING MECHANISM FOR RAILROAD-RAILS.

SPECIFICATION forming part of Letters Patent No. 657,622, dated September 11, 1900.

Application filed April 30, 1900. Serial No. 14,842. (No model.)

To all whom it may concern:

Be it known that I, JOHN J. SHIRKEY, a citizen of the United States, residing at Chicago, in the county of Cook and State of Illinois, have invented certain new and useful Improvements in Ice-Removing Mechanism for Railroad-Rails, which are fully set forth in the following specification, reference being had to the accompanying drawings, forming a part hereof, and in which—

Figure 1 shows the front part of a car *a*, in side elevation, with my device applied in operative position. Fig. 2 shows Fig. 1 in front view. Fig. 3 shows my said device as shown in Fig. 1, on an enlarged scale, applied to the front end of a car. Fig. 4 shows an ice-puncturing wheel in side elevation. Fig. 5 shows a central transverse section of Fig. 4. Fig. 6 shows an ice-cutting wheel in side elevation. Fig. 7 shows a central transverse section of Fig. 6. Fig. 8 shows a side elevation of a wheel provided with transverse ice-cutters. Fig. 9 shows a side elevation, and Fig. 10 a front elevation, of a modified form of construction shown in Fig. 8.

Like reference-letters denote like parts on the drawings.

The object of my invention is to produce a mechanism for removing ice and sleet from the third rail of electric railroads. To attain said desirable end I construct my said new mechanism in substantially the following manner, namely:

Suspended from the car-body *a* by lifting-springs *c* and straps *d* and adjusted to work up and down by a screw *f* in a fixed nut *e* is a pair of superimposed wheel-holding bars *b* *b'*, forced apart by a series of coiled springs *g*. Through said bars and springs pass the stems of the forked wheel-supports *o*, whose shoulders below the bar *b* and heads on the bar *b'* limit the motion of the bar *b*. The front end of said bars is also provided with a steel brush *h*, with stiff brushing mechanism, following which is a wheel *i*^x, provided with radial closely-set sharp steel barbs *i*, and next in order follows a wheel *j*^x, provided with circumferential cutters *j*, and next in order follows a wheel *i'*, having on its rim radially-pointing transverse steel cutters *i'*. The said brush *h* clears the rail of loose snow and ice, the wheel *i* punctures the ice and breaks and flakes it up into small masses,

and the cutters *i* of the wheel *j*^x cut the ice into longitudinal strips, after which the transverse cutters *i'* cut said longitudinal strips into small square blocks, which will break loose from their base.

The diagonal cutters *j* of Figs. 9 and 10 are merely a modification of the transverse cutters *i'* of the wheel *i'* to accomplish practically the same purpose. A sprocket-wheel *m'*, secured to the axle of the wheel *i'*, and a chain belt *m* operate a sprocket-wheel *m*² on the shaft of the cylindrical and revolving brush *l*, which is provided with steel brushing-springs *l*, wherewith every removable particle of ice will be forced from the track or third rail *p*. Said third rail is the well-known third rail used for conducting the current of certain constructions of electric railroads, whereon ice forms a working obstruction.

The bar *b'* is held by straps *d*, attached to the laterally-projecting springs *c*, and a screw *f*, passing through a nut *e*, secured in a rigid bracket, affords means for adjustment of the bars *b* *b'* to and from the track into operative and inoperative condition, while the springs *g* yield to the motion of the bar *b* through the action of said wheels, which yield to the irregularity of the track-surface, and the said action of the said several wheels *i*^x *j*^x *i'* *l* is aided to a considerable degree by the springs *c*, owing to their arrangement with the said screw *f*.

What I claim is—

1. The combination with superimposed, spring-supported and vertically-adjustable bars, of a series of wheels faced with mechanism adapted to comminute ice and sleet on railroad-rails and means to remove said comminuted material, substantially as specified.

2. The combination with superimposed, spring-supported and vertically-adjustable bars thrust apart by springs and held in place to each other by wheel-supports, of a series of wheels in said supports, faced with mechanism adapted to comminute ice and sleet and means to remove said comminuted material from railroad-rails, substantially as specified.

JOHN J. SHIRKEY.
